US00D881235S

(12) **United States Design Patent** (10) Patent No.: **US D881,235 S**
(45) Date of Patent: **** Apr. 14, 2020**

(54) **DISPLAY SCREEN OR PORTION THEREOF
WITH ICON**

- (71) Applicant: **Apple Inc.**, Cupertino, CA (US)
- (72) Inventors: **William Martin Bachman**, San Jose, CA (US); **Taylor Gerard Carrigan**, San Francisco, CA (US); **Alexander C. D. Fringes**, San Francisco, CA (US); **Monika E. Gromek**, Oakland, CA (US); **Ofer Morag**, Oakland, CA (US); **Jeffrey L. Robbin**, Los Altos, CA (US)
- (73) Assignee: **Apple Inc.**, Cupertino, CA (US)
- (**) Term: **15 Years**
- (21) Appl. No.: **29/662,205**
- (22) Filed: **Sep. 4, 2018**

Related U.S. Application Data

- (63) Continuation of application No. 29/615,638, filed on Aug. 30, 2017, now Pat. No. Des. 831,060, which is a continuation of application No. 29/570,462, filed on Jul. 8, 2016, now Pat. No. Des. 797,782, which is a continuation of application No. 29/523,739, filed on Apr. 13, 2014, now Pat. No. Des. 765,118.

(57)

CLAIM

The ornamental design for a display screen or portion thereof with icon, as shown and described.

DESCRIPTION

The sole FIGURE shows a display screen or portion thereof with icon showing our new design.

The peripheral dashed broken lines illustrate a display screen or portion thereof, and form no part of the claimed design.

1 Claim, 1 Drawing Sheet
